(57) **CLAIM**

The ornamental design for a hose, as shown and described.

DESCRIPTION

FIG. 1 is a front perspective view of a hose showing our new design;

FIG. 2 is rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the hose which form no part of the claimed design.

The hose is shown with a symbolic break in its length. The appearance of any portion of the hose between the break lines forms no part of the claim.
